UNITED STATES PATENT OFFICE.

WILLIAM SPINK AND JOSEPH M. BALTZ, OF PHILADELPHIA, PENNSYLVANIA.

TWISTING-MACHINE.

1,030,937.

Specification of Letters Patent.

Patented July 2, 1912.

Application filed June 6, 1911. Serial No. 631,598.

To all whom it may concern:

Be it known that we, WILLIAM SPINK and JOSEPH M. BALTZ, both citizens of the United States, residing in the city and county of Philadelphia, State of Pennsylvania, have invented a new and useful Twisting-Machine, of which the following is a specification.

Our invention consists of an improved reel 10 or twisting machine for twisting two or more strands of yarn and reeling the same.

It further consists of improved means for positively driving the spindles and fliers.

It further consists of improved means for 15 controlling the speed of the spindles so as to drive the same with less speed when drawing strands from the ends of the cops than when drawing from the middles of the same.

It further consists of other novel features 20 of construction, all as will be hereinafter fully set forth.

In machines for twisting a plurality of twisted strands of yarn from the mule and for then reeling it into hanks, it is of great 25 importance that all of the several strands which are twisted into one yarn are twisted alike, as a strand which is twisted harder than the others is liable to kink in twisting and thus form a knot in the yarn, and it is 30 also of importance that the twisted yarn receives the same twist at each flier, so that the several hanks of yarn will come out uniform. Heretofore the fliers and spindles in twisting machines have been driven by end- 35 less cords on pulleys, and the output from such machines has not been absolutely uniform in quality of twist, nor has it been possible to make the output of each flier even, as some fliers, the cords of which were tight, 40 would run faster than those in which the cords have slackened. The consequence of this would be, and is, that certain hanks of yarn come out satisfactory, while others will come out with knots and rough spots in the 45 yarn, and also that some hanks will be finished sooner than others, so that the entire set of spindles will have to be run while only a few fliers are in active operation.

It is for the purpose of obviating these 50 more or less objectionable features, all of which are detrimental in an economical sense to the accomplishment of the greatest output with the least consumption of time and labor, that we have devised our present 55 improvement.

In the accompanying drawings we have

illustrated one form of machine in which our invention may be embodied, but it is evident that the invention may be differently embodied without departing from the spirit of 60 the same.

In the annexed drawings:—Figure 1 represents an end view of our improved twisting machine. Fig. 2 represents an end view of the machine from the end opposite that 65 illustrated in Fig. 1. Fig. 3 represents a horizontal section on the line $x-x$ in Fig. 1, giving a top plan view of the lower part of the machine. Fig. 4 represents a front elevation of the machine, with certain portions 70 of the driving mechanism broken away and removed. Fig. 5 represents a sectional detail view of the pulleys and sprocket wheels of the driving mechanism. Fig. 6 represents a plan view on an enlarged scale, in 75 detached position.

Similar numerals of reference indicate corresponding parts in the figures.

Referring to the drawings: the machine has two end-frames, 1, upon which are supported a front rail, 2, a spindle rail, 3, and a cop-rail, 4. A shaft, 5, is journaled in bracket-bearings, 6, at one end of the machine and has a drive-pulley, 7, secured upon it, which derives rotary motion from 80 a belt, 8, or from other suitable driving source of power. A pulley, 9, is loose upon the shaft, alongside of the fast pulley, and still another pulley, 10, is loose upon the shaft and alongside of said former pulley. 90 A belt-shifter, 11, is provided to shift the belt upon either of the three pulleys. A sprocket-wheel, 12, is secured upon the hub of the inner, loose pulley, 9, and a sprocket-chain, 13, passes around said wheel and a 95 sprocket-wheel, 14, of larger diameter, journaled upon a short countershaft, 15, projecting from the end-frame and parallel to the drive-shaft. A sprocket-wheel, 16, of smaller diameter is secured to said large- 100 diameter wheel 14 and also journaled upon said shaft, and a sprocket-chain, 17, passes around said small wheel and around a sprocket-wheel, 18, secured upon the drive- shaft. A sprocket-wheel, 19, is secured upon 105 the drive-shaft, and a sprocket-chain, 20, passes around said wheel and around a sprocket-wheel, 21, of smaller diameter, which is secured upon a shaft, 22, journaled in a bracket, 23, upon the end-frame. Said 110 shaft has a bevel-wheel, 24, secured upon its end, which meshes with a bevel-wheel, 25,

upon the lower-end of a shaft, 26, journaled in a bracket, 27, upon the end-frame and carrying a sprocket-wheel, 28, upon its upper end. Said latter sprocket-wheel is in a 5 plane above the spindle-rail and a sprocket-chain, 29, passes around said wheel and around a sprocket-wheel 30, at the opposite end of the spindle-rail and having its shaft, 31, journaled in a bracket, 32, upon the end- 10 frame there. The sprocket-chain is supported upon rollers, 33, mounted upon the spindle-rail, and engages small sprocket-wheels, 34, upon main-spindles, 35, of flier-frames, 36, which spindles are stepped in step-bearings, 37, upon the spindle-rail and journaled 15 in bearings in an upper spindle-rail, 38, above the spindle-rail.

Each flier-frame consists of two spiders, 39 and 40, upon the main-spindle, having radiating arms in which cop-spindles, 41, are 20 respectively stepped and journaled. Each cop-spindle has a pinion, 42, upon it, and said pinions mesh with an internal cog-gear, 43, supported upon the upper spindle-rail. 25 The upper ends of the main-spindles carry radiating arms, 44, each formed with two guide-eyes, 45, and all registering with the cop-spindles. Yarn-guides, 46, are supported above the flier-frames in brackets, 47, and 30 each guide corresponding to and registering with a flier-frame. Each yarn passes from the upper yarn-guide to a guide-eye, 48, upon a reciprocating traverse-bar, 49, sliding in bearings upon the front-edge of the 35 front-rail of the machine. A reel, 50, has its shaft, 51, journaled in bearings, 52 and 53, in the end-frames of the machine, and the yarn is passed from the eyes upon the traverse-bar to said reel and is wound in 40 hanks upon the same. A pinion, 54, upon the reel-shaft meshes with a pinion, 55, upon a stub-shaft upon the end-frame, and said latter pinion has a wrist-pin, 56, upon its 45 face, upon which pin the lower end of a pitman, 57, is pivoted. The upper end of said pitman is pivotally connected to a bell-crank, 58, fulcrumed upon the front of the frame, and the other arm of said bell-crank has pivoted to it one end of a connecting rod, 58^x, the other end of which is pivoted to the 50 traverse-bar. A sprocket-wheel, 59, is loose upon the reel-shaft, and a half-clutch, 60 is formed upon the inner face of said sprocket-wheel and engages a half-clutch, 61, sliding 55 upon and rotating with the reel-shaft. Said latter half-clutch has a circumferentially grooved hub, 62, which is engaged by studs, 63, in a frame, 61, encircling said hub and formed in an arm, 65, fulcrumed at its lower 60 end upon the frame and having its upper and pivotally connected to a bar, 66, sliding beneath the front-rail. Said bar has, at suitable distances apart, pairs of forwardly-projecting blocks, 67, between which the 65 lower arms of shifting levers, 68, fulcrumed

upon the front edge of the front-rail, engage, so that the bar may be shifted and the clutch operated from several points along the front of the machine. A sprocket-chain, 69, passes around the sprocket-wheel 59 70 upon the reel-shaft, and passes around a small sprocket-wheel, 70, upon a stub-shaft, 71, projecting from the end-frame, and a sprocket-wheel, 72, of larger diameter is secured to said small wheel and also journaled 75 upon said stub-shaft. A chain, 73, passes around said larger wheel and around a small sprocket-wheel, 74, upon the drive-shaft, so that the reel may thus be driven from said shaft. The bearing 52 for the reel-shaft is 80 formed in the center of a circular frame, 75, having one side open, and revolvably mounted in a semicircular support, 76, in the end-frame, so that the finished hanks, 77, may be removed from the reel at that end. 85

In practice, cops, 78, of yarn from the mule are placed upon the spindles and the yarn is threaded through the several guide-eyes and the several strands from the cops upon each flier are united and drawn through the upper yarn-guides and down through the yarn-guides upon the traverse-bar to the reel, where the ends are secured. When now the machine is started, each spindle revolves and twists its strand, and the joined strands are twisted together in the opposite direction and wound in hanks upon the reel. When starting to unwind from the cops, the belt is thrown onto the inner loose pulley 10, which communicates slow motion to the flier-frames and spindles through the sprocket-wheels and chains, so that the yarn will not be pulled off the cop and tangled. When the work has advanced so far that yarn is unwound from the thicker portions of the cops, fast speed is resumed by shifting the belt on to the outer and fast pulley, and such speed is maintained until the cops are nearly empty, when slow speed is again used. The flier-frames and spindles being positively driven by cogged gearing and sprocket-chains and wheels, said frames and spindles will all be driven at an absolutely uniform rate of speed, so that all the hanks of yarn wound upon the reel will be of uniform twist. This uniformity cannot obtain where belt, cord, or other frictional drive is employed. As the cops are all wound with substantially the same quantity of yarn, all fliers in the machine will finish 105 their work at substantially the same time and all hanks will be finished at about the same time. 110

By providing the device for driving the fliers at slow speed at the beginning and 115 ending of unwinding the yarn from the cops, waste will be prevented from stripping and tangling the yarn at the ends of the cops, and waste will also be prevented by driving the fliers at uniform speed and 120

by positive driving means, while in twisting machines having cord or similar frictional driving means, a large amount of waste is caused by such cords getting slack and slipping upon or off from their pulleys, thereby stopping the fliers and tearing and tangling the yarn, producing waste. Waste forms a considerable item in the cost of spinning woolen yarn, and any means producing a lessening of waste are of great utility in wool-spinning machinery.

The clutch-mechanism upon the reel-shaft is provided for the purpose of disconnecting the reel from the remainder of the machine, so that in removing the banks, the operator shall not be obliged to operate all of the parts of the machine, but can revolve the reel freely and without undue exertion.

As all of the several driving mechanisms are positively driven and co-act in unison, it is necessary to have manual control by the machine operator of the speed-changing devices for the fliers, spindles and reel, that such control may be exercised when the winding from the ends of the cops is started, and for this purpose we have provided manual control of the speed-changing mechanism, as automatic control for such purpose is not practical.

Having thus described our invention, what we claim as new and desire to secure by Letters Patent, is:—

1. In a machine for making woolen yarn, a spinning frame, a series of fliers mounted in line upon said frame, a unitary means for synchronously driving such series of fliers, cop-spindles journaled in said fliers, stationary gears, one for each flier, and engaging the spindles of the same to drive them in the opposite direction to that of the fliers, a unitary reel parallel to the line of the fliers, and means for rotating said reel synchronously with the fliers.

2. In a machine for making woolen yarn, a spinning frame, a series of fliers mounted in line upon said frame, a unitary means for synchronously and positively driving such series of fliers, cop-spindles journaled in said fliers, stationary gears, one for each flier, and engaging the spindles of the same to positively drive them in the opposite direction to that of the fliers, a unitary reel parallel to the line of the fliers, and means for positively rotating said reel synchronously with the fliers.

3. In a machine for making woolen yarn,

a spinning frame, a series of fliers mounted in line upon said frame, a unitary means for synchronously driving such series of fliers, cop-spindles journaled in said fliers, 60 stationary gears, one for each flier, and engaging the spindles of the same to drive them in the opposite direction to that of the fliers, a unitary reel parallel to the line of the fliers, means for rotating said reel synchronously with the fliers, and manually controlled means for simultaneously changing the speed of such fliers and reel, whereby the machine will be controlled to run at slow speed when the unwinding of the cops is 70 begun and finished and at high speed when the bodies of the cops are unwound.

4. In a machine for making woolen yarn, two parallel series of main spindles, a unitary means for synchronously and positively 75 driving such spindles, spiders secured upon said spindles, cop-spindles journaled in said spiders and carrying pinions, stationary internal gears secured concentric with said main spindles and engaged by the pinions, 80 a unitary reel parallel to the series of main-spindles, and means common to said spindle-driving means and said reel for synchronously and positively driving the same.

5. In a machine for making woolen yarn, 85 a series of aligned main-spindles, a plurality of cop-spindles upon said latter spindles, a unitary means for synchronously rotating said main-spindles, a sprocket wheel 21 connected to actuate said means, a drive-shaft 90 5, a pulley 7 fast upon said shaft, an idle pulley 9 loose upon said shaft, a pulley 10 loose upon said shaft and carrying a sprocket-wheel 12, sprocket-wheels 18, 19 and 75 secured upon the shaft, a driving belt 95 adapted to engage either of said three pulleys, a belt-shifter, a countershaft 15 carrying a larger sprocket-wheel 14 and a smaller sprocket-wheel 16, a chain 13 around wheels 14 and 12, a chain 17 around wheels 16 and 100 18, a chain 20 around wheels 19 and 21, a large sprocket wheel 72 carrying a small wheel 70, a chain 73 around the wheels 72 and 74, a reel 50 having a shaft 51, a sprocket wheel 59 upon said shaft, and a sprocket 105 chain 69 around the wheels 59 and 70.
